UNITED STATES PATENT OFFICE.

JOSEPH ROSSI, OF PHILADELPHIA, PENNSYLVANIA.

SOUND-REPRODUCING MACHINE.

1,385,475.

Specification of Letters Patent. Patented July 26, 1921.

Application filed December 22, 1919. Serial No. 346,624.

To all whom it may concern:

Be it known that I, JOSEPH ROSSI, a citizen of the United States, residing at Philadelphia, in the county of Philadelphia and 5 State of Pennsylvania, have invented certain new and useful Improvements in Sound-Reproducing Machines, of which the following is a specification.

One object of my invention is to provide 10 a sound reproducing machine which will be particularly adapted for use in theaters or amusement houses for use in connection with motion pictures and so that exceptionally long records can be used thereon so as to 15 continue the reproduction throughout an entire picture or for a long portion thereof.

Another object is to so construct my invention that the sound reproduced thereby will be distinctly audible to a large audience.

20 A still further object is to so construct my invention that it will include a plurality of reproducing needles or similar elements, any of which can be replaced during the reproduction of the record without interrupting the continuity of the reproduction.

These objects, and other advantageous ends which will be described hereinafter, I attain in the following manner, reference being had to the accompanying drawings in 30 which—

Figure 1 is a perspective view showing my improved sound reproducing machine in operative position relatively to a motion picture screen,

35 Fig. 2 is an enlarged fragmentary perspective view of each of the parts of my invention,

Fig. 3 is a fragmentary detached perspective view showing a portion of the record 40 and its connecting elements,

Fig. 4 is an enlarged fragmentary section taken on the line 4—4 of Fig. 2,

Fig. 5 is a fragmentary perspective view showing two reproducing needles simultaneously in engagement with the record,

Fig. 6 is a fragmentary perspective view showing the sound box removed, and

Fig. 7 is a perspective view illustrating one of the conveying collars which I prefer- 50 ably use.

Referring to the drawings, 8 and 8^a are pedestals which form a supporting structure and bearing for two rotatably mounted shafts 9 and 10; said shafts extending between the pedestals 8 and 8^a and being continuously screw threaded as illustrated.

The shafts 9 and 10 are adapted to be rotated by belts 11 and 12 from a pulley 13 on a main operating shaft 14; said operating shaft 14 being operatively connected to an 60 electric motor 15. The shaft 14 is rotatably mounted in the pedestal 8 and has a clamping band 16 secured thereon by a set screw 17. The clamping band 16 is adapted to be connected to the end 18 of a long cylindrical 65 record 19 by means of screws 20 or other suitable devices, such for example as shown in Figs. 1 and 3. Another clamping band 21 is secured to the opposite end of the record 19; said clamping band 21 being mounted on 70 a shaft 22 which serves as a continuation of the main operating shaft 14 and is mounted in the pedestal 8^a.

A cabinet 23 is connected to two transverse bars 24 and 25; said transverse bars 75 having conveying collars 26 on opposite ends; said conveying collars being provided with screw threaded holes 27 for engagement with the threaded portions of the shafts 9 and 10. These conveying collars are made 80 in sections which are hinged together, as shown in Fig. 7, so that the sections can be opened up to permit the detachment of the cabinet 23 from the shafts 9 and 10. The cabinet is positioned below the record 19 and 85 at its back has a hollow standard 28 to which is pivotally connected a tone arm 29. The tone arm 29 has two forwardly diverging hollow branches 31 and 32. These branches adjacent their forward ends are turned in- 90 wardly, as shown at 33, and are provided with flanges 34.

Two sound boxes 35 and 36 are positioned between the flanges 34; said sound boxes having hollow extensions 39 which are rotatably mounted within the respective flanges of the branches 31 and 32. In this manner either of the sound boxes 35 and 36 can be independently rotated for a purpose hereinafter described. Each of the 100 sound boxes has a reproducing needle 38 and either of these needles can be moved into engagement with the record 19. The record 19 is preferably made by including two helical grooves; the turns of one groove 105 being positioned between the turns of the other groove so that both of the grooves will produce similar tones at the same time. In other words, the grooves are arranged similarly to the double threads of a screw 110 and so that if both of the needles are moved into engagement with adjacent portions of

the two grooves, for example as shown in Fig. 5, each of the needles will transmit the same sound.

With this arrangement it is possible to change either of the needles 38 without stopping the machine or without interrupting the continuity of the reproduction of the record, since it is merely necessary to swing either of the sound boxes 35 or 36 so that its needle is moved out of engagement with the record into a position to permit a new needle to be inserted and this can be done without stopping the machine. Fig. 2 shows the needle of the sound box 36 having been raised into a position so as to permit changing, such as above described. The forward portion of the cabinet 23 is provided with outlet openings 39 so that the sound passing through the tone arm and downwardly through the hollow standard 28 will pass outwardly from the cabinet through the openings 39.

With the above mentioned construction, the pedestals 8 and 8^a can be positioned a comparatively great distance apart so that an extremely long cylindrical record 19 can be employed. This arrangement permits the machine to be placed close to a motion picture screen, such for example as shown at 40 in Fig. 1, and if desired the character of the reproductions can be varied to suit the picture which is projected upon the screen.

While I have described my invention as taking a particular form, it will be understood that the various parts of my invention may be changed without departing

from the spirit thereof, and hence I do not limit myself to the precise construction set forth, but consider that I am at liberty to make such changes and alterations as fairly come within the scope of the appended claim. 40

Having thus described my invention, what I claim as new and desire to secure by Letters Patent is:— 45

A machine of the character described including an elongated rotatable record; two shafts spaced apart and extending in the direction of the length of the record, at least one of said shafts being rotatable and having screw threads; a cabinet having a sound outlet; reproducing means carried by the cabinet and adapted to engage said record whereby the reproduced sound will pass out of said outlet; and transversely extending suspension means for said cabinet having parts engaging said shafts whereby the cabinet is supported jointly by said shafts, said parts having screw threaded portions for engaging said shaft screw threads, said parts being located adjacent opposite sides of the cabinet whereby the cabinet is supported at distances apart in the direction of the lengths of said shafts; substantially as described. 55

In testimony whereof I have signed my name to this specification in the presence of two subscribing witnesses.

JOSEPH ROSSI.
